UNITED STATES PATENT OFFICE.

MASUNOSUKE SAKOGAWA, OF OAKLAND, CALIFORNIA.

TOILET-FLUSHING DEVICE.

1,308,301.

Specification of Letters Patent.

Patented July 1, 1919.

Application filed January 31, 1917. Serial No. 145,717.

To all whom it may concern:

Be it known that I, MASUNOSUKE SAKOGAWA, citizen of the United States, residing at Oakland, in the county of Alameda and State of California, have invented certain new and useful Improvements in Toilet-Flushing Devices, of which the following is a specification.

My invention is a new and improved 10 toilet constructed and arranged to eliminate the annoying and embarrassing noise caused by the rush of the flushing water therethrough.

In the accompanying drawing, which 15 forms part of this specification and the appended claims,

Figure 1 is a sectional elevation of my improved noiseless toilet.

Fig. 2 is a fragmentary sectional view of 20 a flush tank constructed in accordance with my invention showing upper bumper and engaging means for the tank valve.

Numeral 1 indicates a toilet base which 25 may be made as usual of porcelain. The base has a large inlet conduit 2 leading into the front of the usual bowl 3, in the top of the base, and a large outlet conduit 4 leading from the rear of the bowl and to the outer end of which is connected an outlet pipe 5.

30 To the inlet end of the inlet conduit is connected an inlet pipe 6 which leads from the lower part of a flush tank 7. A supply pipe 8 leads into the bottom of the flush tank and is adapted to supply water into the tank. A valve 9 is hinged to the discharge end of the supply pipe 8 within the flush tank. The valve has an arm 10 which is connected by a cord 11 to a float 12, the buoyancy of which float is adapted to pull 35 the string and arm upwardly and close the valve to shut off the supply of water from the supply pipe 8 into the tank when the tank is full of water. A controlling glass slab slide valve 13 is slidably mounted in the tank and is adapted normally to extend 40 across the end of the pipe 6 and prevent water from flowing from the tank through said pipe and inlet conduit 2 into the bowl 3. The sliding action of the glass valve is 45 noiseless.

A cord 14 is connected to the valve 13 and passes over pulley 15 in the tank, then through an opening in the tank, and then over pulley 16 outside the tank. A handle 17 is secured to the outer end of the cord 55 which may be grasped and pulled downwardly to raise the valve 13 to admit water into inlet pipe 6 and inlet conduit 2 to flush the bowl 3.

A rubber bumper 18 is provided in the 60 tank, against which the glass valve 13 is adapted to drop, upon closing the pipe 6, whereby noise and breakage of the valve upon dropping is prevented. A bumper 20 is provided in the top of the tank to arrest 65 the upward opening movement of the glass valve and prevent noise and breaking of the valve when so arrested. The bumper has an extension 21 to engage the rear of the valve at the top to prevent the upper end of 70 the valve from falling rearwardly when in its extreme upper position.

When the valve 13 is opened and the water passes out of the tank through pipe 6 and conduit 2 to flush the bowl 3, the float 12 75 descends and the cord 11 ceases pulling on the arm 10, whereupon the force of the water in supply pipe 8 opens the valve 9, and the water discharges from said pipe into the tank until the tank is again filled 80 and the float closes the valve 9.

The inlet and outlet conduits 2 and 4 extend in a tortuous direction through the base 1 which formation of the conduits serves to eliminate objectionable noise of the 85 water which rushes through the conduits in flushing the bowl. Said conduits, and the pipes 8, 6 and 5, are of larger cross sectional area than the cross sectional area of the corresponding conduits and pipes of other 90 toilets, which also serves to eliminate noise of rushing water through the pipes and conduits. Noise is further eliminated in the toilet by the noiseless action of the glass valve 13. 95

Having described my invention, I claim as new and wish to secure by Letters Patent:

1. A toilet comprising a base formed with a bowl and with a large tortuous inlet conduit and a large tortuous outlet conduit, 100

leading to and from said bowl respectively, and means for flushing the toilet through said inlet conduit, bowl and outlet conduit.

2. A toilet comprising a base formed with a bowl and with a large tortuous inlet conduit and a large tortuous outlet conduit

leading to and from said bowl respectively, and noiseless means for controlling the introduction of water through said inlet conduit, bowl and outlet conduit.

In testimony whereof I affix my signature. 10
MASUNOSUKE SAKOGAWA.
